UNITED STATES PATENT OFFICE.

JOHN PAXTON PETTY, OF CROWTHORNE, ENGLAND.

SHEET-FEEDING MECHANISM.

1,303,592.

Specification of Letters Patent. Patented May 13, 1919.

Application filed December 12, 1916. Serial No. 136,581.

To all whom it may concern:

Be it known that I, JOHN PAXTON PETTY, a subject of His Majesty King George V, of the United Kingdom of Great Britain and 5 Ireland and of the British Dominions beyond the Sea and Emperor of India, residing at Crowthorne, Berkshire, England, have invented certain new and useful Improvements in Sheet-Feeding Mechanism, of 10 which the following is a specification.

The present invention is for automatically feeding paper sheets and the like flat articles (hereinafter termed sheets) to machines.

For this purpose I adopt means by which 15 the upper sheets of a pile are successively freed and bodily floated upwardly to directly or/and indirectly derive motion frictionally from the under aspect of a frictional sheet forwarding device situated above 20 the pile and formed and operating so as to advance the sheet toward or into the inway of the machine to be fed.

The successive sheets directly derive motion frictionally from the under aspect of 25 the sheet forwarding device in cases where the sheets are desired to be serially forwarded, *i. e.*, in non-stepped sequence, but in other cases the frictionally effected motion 30 may be indirectly or partly indirectly and partly directly derived from the forwarding device, as in the case where it is desired to forward the sheets in stepped or lapped sequence to apparatus in which the top sheet of the stepped sequence of sheets is first 35 taken in and is thereby turned over for rapid individual delivery or dropping on to a "knocking-up" board, such as is shown, for example, in applicant's copending application, Serial No. 873,597, filed November 40 23, 1914.

In this last mentioned case the upper sheets of a pile must be so successively freed and bodily floated upwardly as to follow each other in lapped order into the inway 45 of the machine being fed, the mutual resistance to relative motion which in the first mentioned case is produced directly between the sheet and the forwarding device now being produced between the sheets themselves 50 as well as between the sheets and the forwarding device.

As an example of a forwarding device which will serve for the purposes of the present invention, the following may be men-

tioned, viz., a horizontally disposed series 55 of parallel rollers situated above the sheet-pile, these rollers being ranged, and being mounted and connected to revolve in the appropriate direction for frictionally coöperating with the sheets, to forward or direct 60 these in the desired direction.

Alternatively an endless traveling belt or band or tape or like system may serve. These examples are not however to be regarded as in any way limiting the scope of 65 the invention since the means by which it is carried into effect may vary widely. But for the purposes of the following description of a convenient and advantageous way 70 of carrying the present invention into practice and which has been found to work well the forwarding device consisting of the above mentioned horizontally disposed series of rollers is chosen for reference.

A pile of sheets having been placed on the 75 pile-board of any machine into which the sheets are to be regularly and automatically fed in stepped sequence as hereinabove defined, the following operations and their timing are produced and controlled by appropriate mechanism provided therefor.

Behind and near to the extremities of the back edge of the pile (this back edge being taken as that edge of the pile most remote from the inway of the machine) are blowers 85 which come into action and project currents of air into the back marginal portion of the upper part of the pile to loosen the sheets, particularly the back marginal portions of the upper sheets, and thereby facilitate the 90 action of suction lifters which are situated above the back marginal portion of the pile and near or toward the extremities of the back edge of the pile. The blowers will ordinarily be adjustable in relation to the back 95 edge of the pile, and when adjusted their position may be fixed. Alternatively they may be made movable and connected to the driving mechanism of the machine so as to have hunting action in relation to the back edge of the pile as by movement vertically upward and downward or back and forth along the back edge either obliquely thereto or parallel therewith, or both, or by orbital movement.

The air blast from the said blowers may be varied to suit different weights of paper and for this purpose provision may be made

to afford a controlled adjustment of the air blast. As an example a stop cock which can be set in various positions for controlling the flow may be mentioned.

- 5 During the aforesaid blowing or loosening or separating action, the suction-lifters are moved downward to bear on the pile and on taking this bearing on the pile they are constrained to dwell somewhat in this position with the object of rendering the suction-lifters more effective in their function of lifting up the back of the upper sheet of the pile as they rise therefrom. This bearing on the pile has a further purpose in that
- 10 15 the loosened back marginal portions of the upper sheets of the pile, or, as the pile exhausts itself of all the remaining sheets of the pile, are pressed back to normal level to present a level pile surface for the introduction of presser feet presently to be referred to, the pressure requisite for this purpose not being such as, and the pressure not being so as, to count adverse to the invention by forming subversive adhesions.
- 20 25 The bearing of the suction-lifters on the pile synchronizes more or less with the cutting off of the blowers: simultaneously suction action commences at the nozzles of the suction-lifters. As conducing to a higher realization of the end or aim of the invention, the nozzle-mouths are arranged so as to draw the back marginal portion of the top sheet generally or locally to themselves by a bending away of such portion from the pile so as to expose the corresponding back marginal portion of the next underlying sheet of the pile and so as to insure sucking one sheet only at a time. In this connection, for a given resultant suction pull, I have
- 30 35 40 45 50 found by arranging the planes containing the boundaries of the nozzle-mouths to be more nearly parallel or less nearly parallel to the plane of the sheet, and the nozzle-mouths bodily less near or more near to the sheet respectively, I am able to accommodate the invention to different weights of sheets, and speaking generally the heavier the stock the more nearly parallel will the said planes and the more near the sheet will the nozzle-mouths require to be.
- Hence the suction nozzles will usually be adjustable for angle and distance in relation to the plane of the sheets and this adjustment may be made under the guidance of a graduated scale fitted to the appropriate part of the mechanism or it may be made by trial in relation to any given stock or by both methods, it being understood that the suction nozzles have or are companion with presser feet for bearing on the pile in the manner and for the purposes above mentioned.
- Additionally or alternatively there may be provision for varying the amount of the vacuum to suit any given work.

Having caused the back marginal portion of the top sheet of the pile to adhere to their nozzles, the suction-lifters at the end of their dwell commence to rise, and in rising further expose the back portion of the next underlying sheet: simultaneously with or at or about the commencement of the rising stroke of the suction-lifters, presser feet as above mentioned move forward toward the back edge of the pile and enter between the raised back marginal portion of the top sheet and the pile and grip the latter to thereby hold this as a pile against disturbance.

Conveniently the presser feet form blowers by which currents of air are projected under the raised top sheet to thereby fully free it from the pile and bodily float or bodily drive it upwardly by a rising air blast to the revolving rollers situated above the pile and functioning to frictionally advance the sheet into the inway of the mechanism or into the inway of withdrawing or delivering means generally, the said further blowers conveniently or ordinarily continuing in action until the machine or other receiving means has taken the sheet into its control.

As in the case of the first mentioned blowers facilities may be provided to vary the air blast from said further blowers to suit various weights of paper.

At or about the time the presser feet are effective on the pile, a secondary presser foot bearing on the top of the pile somewhat forward of the first mentioned presser feet is actuated to release the pile and thereby leave the raised top sheet unhindered from being floated or air-driven upwardly as described.

Conveniently and advantageously this secondary presser foot will be arranged to function as a feeler for the height of the pile and through the intermediary of suitable connections to control means functioning for the automatic elevation of the pile board.

The drawings illustrate a constructional form under the invention.

Figure 1 is a side elevation of the machine.

Fig. 2 a view of the right hand portion of the suction, presser, and air blast devices looking from left to right of Fig. 1.

Fig. 3 is a side view of the suction, presser, and air blast devices.

Fig. 4 is a view of the general driving gear for imparting motion to the various parts of the machine.

Fig. 5 shows a sheet in the act of being raised from the pile, while,

Fig. 6 is a diagrammatic view of the timing and controlling cams and their relation one to the other.

In the machine illustrated it is to be understood that the suction, presser, and air blast devices are employed in duplicate and equi-

spaced from the center line $x-x$ Fig. 2, those to the left of $x-x$ Fig. 2 not being shown.

The sheet forwarding device in the machine illustrated comprises a horizontally disposed series of parallel rollers 1 situated in side bearings 2 above the sheet pile, these rollers deriving motion from a main driving shaft 3, by a chain drive 4, 5 and 6, the drive being in an appropriate direction as indicated by the arrow 7 in Fig. 4. The rollers 1 frictionally coöperate with the sheets, to forward these in the desired direction to delivery apparatus 8, 9 for automatically and regularly feeding the sheets.

10 10 is an automatic rising pile board (shown in the raised position) on which the pile of sheets is placed. Behind and near to the extremities of the back edge of the pile, are blowers 11 in communication for example, by flexible hose with a stop cock 12 which in turn is connected through the hollow shaft 12^a to a suitable blower not shown. A revolving shaft 13 driven from the shaft 3 by spur and bevel gearing 13^a, 13^b, 13^c, has a 20 timing cam 14 thereon for operating said stop cock through lever mechanism 15 loose on shaft 15^a whereby the blowers 11 come into action at the appropriate time and project currents of air into the back marginal portion of the upper part of the pile to loosen the sheets, particularly the back marginal portions of the upper sheets and thereby facilitate the action of the suction-lifters hereinafter referred to. The blowers 11 are 30 adjustable (see Fig. 3) in a bracket on shaft 17^a in relation to the back edge of the pile and when adjusted their position in the depicted case is fixed.

During the aforesaid blowing or loosening or separating action, suction-lifters 16, mounted at the opposite ends of a pipe 16^a capable of angular adjustment in the forward end of a pivoted arm 17 loose on shaft 17^a, move downward under the action of a 40 timing and controlling cam 18 mounted on shaft 13 and connecting parts (pivoted lever 19, loose on shaft 15^a, and link 20), to bear with their presser feet 16^a on the pile, and on taking this bearing on the pile they are 45 constrained to dwell somewhat in this position with the object aforesaid. The bearing of the suction-lifters 16 on the pile synchronizes more or less with the cutting off of the blowers 11: simultaneously suction action commences at the nozzles 16^b of the suction-lifters 16. This suction action is effected by means of a stop cock 21 which is connected through the hollow pipe 12^a to a suitable suction apparatus, not shown, and is operated 50 through an opening lever 23 by a timed controlled cam 22 on the shaft 13. The nozzle mouths 16^b are inclined so as to draw the back marginal portion of the top sheet generally or locally to themselves by a bending 55 away of such portion from the pile so as to

expose the corresponding back marginal portion of the next underlying sheet of the pile and so as to insure sucking one sheet only at a time. The suction nozzles 16^b are arranged adjustable for angle and distance in relation to the plane of the sheets by pin and arcuate slot 24 and 24^a and lug 24^b, and screwed connection 25 respectively.

Having caused the back marginal portion of the top sheet of the pile to adhere to their nozzles, the suction lifters 16, 16^a, at the end of their dwell commence to rise by virtue of the timing cam 18 and in rising further expose the back portion of the next underlying sheet. Simultaneously with, or at or about 70 the commencement of the rising stroke of the suction-lifters, presser feet 26 each pivotally mounted on the lower end of a spring controlled lever 28 under the influence of a cam 27 on the axis 13, are moved forward toward 75 the back edge of the pile and enter between the raised back marginal portion of the top sheet and the pile, and press on the latter to thereby hold this as a pile against disturbance.

80 Mounted by the side of each lever 28 and arranged to be moved therewith is a second similarly spring controlled pivoted lever 33 having a forked end engaging with a pin 34 on each gripper 26. The other end of 85 said lever 33 is under the control of a cam 35 on the axis 13, (cam 35 being shown as of enlarged diameter in Fig. 3 for clearness). These cams 35 are so timed to operate on the levers 33 that during the period 90 of rest of the presser feet 26 in their forward position, the forked ends of said levers 33 swing the presser feet 26 downwardly, to cause these to grip the pile for the purpose described. At the termination of the 100 forward rest period the control cams 27 and 35 allow the levers 28 and 33 to withdraw the presser feet to normal position.

105 Each presser foot 26 in the example illustrated forms also a blower 29 by which currents of air are projected under the raised top sheet to thereby fully free it from the pile and float it upwardly to the revolving rollers 1 forming the frictional sheet forwarding device. Said blowers 29 are in 110 communication as by flexible hose with a stop cock 30 which is connected with the hollow shaft 12^a and is controlled and operated through lever mechanism 31 by a cam 32 on the revolving shaft 13, and are ordinarily continued in action until the machine or other receiving means has taken the sheet into its control. The hollow shaft 12^a is suitably partitioned to serve for both exhaust and pressure and levers 15, 23, and 31, 115 120 also 19 swing loosely on said shaft.

125 At or about the time the presser feet 26 are effective on the pile, secondary presser feet 36 at the forward ends of arms 38 bearing on the top of the pile somewhat forward 130

of the first mentioned presser feet are each actuated by an appertaining cam 37, this cam 37 rocking the shaft 38^a through the lever 13^b fast therewith and thereby raising 5 the arm 38 and with it the presser 36 to release and clear the pile and leave the raised top sheet unhindered from being floated or air-driven upwardly as described.

These secondary presser feet 36 are arranged to further function as feelers for the height of the pile and through the intermediary of suitable connections to control means functioning for the automatic elevation 10 of the pile board 10. The connections 15 depicted are as follows:—

Each arm 38 is fast with the rock shaft 38^a to move therewith, also fast with the rock shaft 38^a is the lever 13^b actuated by the cam 37. To the side of the lever 13^b 20 is a hammer arm 43 which is also fast with the rock shaft 38^a. This hammer arm 43 is arranged so that when the height of the pile has fallen below adjusted feeding level it strikes a counter-poise arm 39 having a locking shoulder 39^a which normally engages a side projecting pin 51 of an arm 42 which is loose on the rock shaft 38^a and carries a pawl 41 engaging a ratchet wheel 44. Thus the pawl lever 42 is tripped and 25 falls back up to a stop lug on a short arm 55 which is fast with the rock shaft 38^a. In doing this the pawl 41 passes back over one or more teeth of the ratchet wheel 44, and at the next actuation of the rock arm 35 13^b by the cam 37, the arm 55 causes the pawl 41 to be advanced to the limit of the rock arm 55, the ratchet wheel 44 becoming thereby rotated one or more teeth, while at the end of this movement the counter-poise 30 arm 39 reengages the pin 51.

Through intermediate gearing 45 this rotation of the ratchet wheel 44 is transmitted to a shaft 46 having toothed wheels 47 thereon engaging racks 48 on which the pile-board 10 is mounted and thus the height of the pile-board is automatically elevated.

Adjustment for spongy or hard piles, to keep the level of the top sheet correct in relation to the inway of the machine being 45 fed, is made by raising or lowering the screw-in stud 52.

All the mechanism forming the machine as above described is so mounted on a bed plate 49 as to be bodily movable by rack 55 and pinion mechanism 50 as to accommodate the mechanism for various sizes of sheets in practice.

All cam actuated and controlled parts may be spring returned or alternatively the cams 60 may be of the internal type.

If the cycle of operations be referred to angular displacements of the controlling axis 13, it may be stated, referring to Fig. 6, for appropriate mechanism provided for 65 producing and timing the operations in rela-

tion to one revolution of this axis, that the following timing gave good results:—

(a) Blowing against edge of pile 0° to 200°.

(b) Suction 90° to 315°.

(c) Suction-lifters rising at 240°, returning 0°.

(d) Back edge presser feet starting forward at 270°, gripping pile at 315°, releasing pile at 140°.

(e) Floating blast on at 270°, off at 90°.

(f) Secondary presser feet on at 125°, off at 320°.

Fig. 5 illustrated a pile of sheets placed on the pile board with the top sheet being 80 acted upon by the nozzles of the suction-lifters. It will be observed the nozzle mouths are so arranged as to draw the back marginal portion of the top sheet generally or locally to themselves by a bending away 85 of such portion from the pile, so as to expose the corresponding back marginal portion of the next underlying sheet of the pile and so as to insure sucking one sheet only at a time.

Facilities may be provided for varying the air blast from the said blowers to suit various weights of papers.

Or alternatively or in addition the height of the frictional forwarding device above 95 the top of the pile is suitably arranged to be varied. A medium distance is about one inch.

What I claim is:—

1. In a machine of the character described, 100 in combination, a table adapted to receive a pile of sheets, pneumatic means operating upon the marginal portion of said pile to loosen and separate the edges of sheets thereon, suction means for engaging and raising the uppermost sheet of said pile in the proximity of said marginal portion, pneumatic means acting from the time of said engagement for raising the portion of said sheet beyond said engaging portion and then completing the separation of said uppermost sheet from said pile after said suction means has commenced its raising function and automatic mechanical means operative immediately under said raised sheet for retaining 105 the remaining sheets of said pile in position thereon.

2. In a machine of the character described, 120 in combination, a feeding table adapted to receive a pile of sheets, pneumatic means operating upon the marginal portion of said pile to loosen and separate the edges of sheets thereon, suction means for engaging and raising the uppermost sheet of said pile, and pneumatic means for completing the 125 separation of said uppermost sheet from said pile, said last-mentioned pneumatic means being combined with mechanical means operative to retain the remaining sheets of said pile in position thereon.

3. In a machine of the character described, in combination, a feeding table adapted to receive a pile of sheets, pneumatic means operating upon the marginal portion of said pile to loosen and separate the edges of sheets thereon, suction means for engaging and raising the uppermost sheet of said pile in the proximity of said marginal portion, conveying means presenting a substantially continuous moving surface, and pneumatic means at substantially the level of the top sheet and coming into operation with said suction means for completing the separation of said uppermost sheet from said pile and for bodily forcing and maintaining said sheet in engagement with said moving surface. 60
4. In a machine of the character described, in combination, a feeding table for receiving a pile of sheets, a nozzle adapted to direct an air blast against the upper marginal portion of said pile, thereby to loosen and separate the edges of the sheets thereon, a suction nozzle for engaging and raising the uppermost sheet from said pile, primary presser feet adapted to engage said pile immediately underneath said raised sheet to retain the remaining sheets of said pile in position thereon, an additional nozzle for directing an air blast when the suction nozzle commences engaging the pile to completely remove said uppermost sheet from said pile substantially during the operation of said primary presser feet, and secondary presser feet adapted to engage said pile initially to maintain the latter intact during at least a portion of the operation of said first-mentioned nozzle. 70
5. In a machine of the character described, in combination, a feeding table adapted to receive a pile of sheets, pneumatic means operating upon the marginal portion of said pile to loosen and separate the edges of sheets thereon, suction means for engaging and raising the uppermost sheet of said pile, conveying means presenting a downwardly facing and substantially continuous moving surface, and pneumatic means for directing a blast of air underneath said raised sheet to force the latter bodily upwardly and maintain it in engagement with said moving surface. 80
6. In apparatus of the character described, in combination, a pile of sheets, a blower for separating the marginal edges of the top sheets thereof, a suction means engaging said pile back of said marginal edges for raising the top sheet, a second blower, means for interposing the same between the separated marginal edges of the top sheet and the rest of said pile, and to one side of said suction means whereby said second blower will assist said suction means in overcoming the cohesion between said top sheet and those below it. 85
7. In a machine of the character described, in combination, a pile board for receiving a pile of sheets, a suction nozzle adapted to descend upon said pile and to dwell thereon to engage and raise the uppermost sheet from said pile, primary presser feet adapted to engage said pile immediately underneath said raised sheet to retain the remaining sheets in position, each of said primary presser feet having combined and integral therewith a nozzle for directing an air blast underneath said raised sheet to remove said uppermost sheet from said pile, and secondary presser feet for engaging said pile substantially previous to the operation of said suction nozzle to retain said pile intact. 90
8. In a machine of the character described, in combination, a pile board for receiving a pile of sheets, a suction nozzle for engaging and raising the uppermost sheet from said pile, presser feet for engaging said pile immediately underneath said uppermost raised sheet to retain said pile intact, conveying means presenting a downwardly facing substantially continuous moving surface, each of said presser feet having combined and integral therewith a nozzle for directing an air-blast underneath said raised sheet thereby to bodily force and maintain said sheet in engagement with said moving surface. 95
9. In a machine of the character described, in combination, a pile board for receiving a pile of sheets, a suction nozzle for engaging and raising the uppermost sheet from said pile, presser feet for engaging said pile immediately underneath said uppermost raised sheet to retain said pile intact, conveying means presenting a downwardly facing substantially continuous moving surface, and a nozzle for directing an air-blast underneath said raised sheet thereby to bodily force and maintain said sheet in engagement with said moving surface. 100
- In testimony whereof, I affix my signature. 110

JOHN PAXTON PETTY.
